UNITED STATES PATENT OFFICE.

LUKE L. ROBERTS, OF BRUNNER, TEXAS.

STILT.

SPECIFICATION forming part of Letters Patent No. 738,240, dated September 8, 1903.

Application filed May 9, 1902. Serial No. 106,632. (No model.)

To all whom it may concern:

Be it known that I, LUKE L. ROBERTS, a citizen of the United States, residing at Brunner, in the county of Harris and State of Texas, 5 have invented a new and useful Stilt, of which the following is a specification.

This invention relates to stilts.

The object of the invention is to provide a stilt in which the step or foot-support shall 10 be associated with the pole in such manner as to permit of its ready longitudinal adjustment thereon and its positive securement in its adjusted position; furthermore, to provide a stilt which shall combine simplicity of 15 construction with high efficiency and durability in use and cheapness of production.

Another principal object of my invention is to eliminate the jar commonly produced at 20 every step when stilts with rigidly-fastened steps are used.

With these and other objects in view, as will appear as the nature of the invention is better understood, the same consists in the novel construction and combination of parts 25 of a stilt, as will be hereinafter fully described and claimed.

In the accompanying drawings, forming a part of this specification, and in which like numerals of reference indicate corresponding 30 parts, there are illustrated eight forms of embodiments of the invention, each capable of carrying the same into practical operation, it being understood that the elements therein exhibited may be varied or changed as to 35 shape, proportion, and exact manner of assemblage without departing from the spirit thereof, and in the drawings, Figure 1 is a view in perspective of a stilt embodying one form of the invention. Figs. 2, 3, 4, 5, 6, 7, 40 and 8 are similar views of modified forms of the device.

Referring to the drawings and to Fig. 1 thereof, 1 designates a pole which is preferably rectangular in cross-section and is provided on two of its opposite sides with series 45 of stops or notches 2 and 2^a, which may be constructed as shown or otherwise and are arranged in staggered order with relation to each other. Adjustably connected with the 50 pole is the step or foot-support 3, the lower inner end of which is provided with a projection or offset 8 to engage with the series of

stops 2^a. Secured to the foot-support is a stop-engaging device composed of two members, a stop-engaging member 10 and a pole 55 engaging or clamping member 11. These members are by preference made of wire, and the stop-engaging member 10 is bent to lie against the sides of the pole, thence laterally outward to lie against both sides of the step, 60 with which it is held firmly associated by suitable fastening means, as staples 12, and thence rearward along the side of the step to a point slightly within the pole, where its terminals are formed into eyes 13 to engage 65 loops 14 of the clamping member 11, which latter is provided with two members 15 and 16 to bear against the rear edge of the pole and with two members 17 to bear against the sides of the pole, the latter members being 70 provided with loops 14. It is to be understood that in this figure, as well as in Figs. 2 and 3, the parts of the step-support are duplicated on the opposite side of the stilt, and as this will be readily understood but one side of the 75 stilt is shown. It will be observed that the lower arms 18 of the stop-engaging member are free from attachment of the step from the bend 19 back to the loop of the clamping member, the natural tendency of the arms 18 80 being to force the clamping member downward, and thus into engagement with the pole, thereby operating to bind the offset 8 firmly within its stop. To effect adjustment of the step shown in Fig. 1 the clamping member 85 is forced upward, thereby pushing the offset out of engagement with its stop and at the same time the stop-engaging member 10 out of engagement with its stop, and by drawing back upon the latter member the step 90 may be adjusted longitudinally on the pole in either direction desired.

In the form of embodiment of the invention shown in Fig. 2 the step-engaging member 20 is substantially the same as that shown 95 in Fig. 1; but the arms 18 instead of being extended back to the pole terminate about midway of the length of the step and are provided by eyes or bends 21 to be engaged by the terminals of a pair of arms 22, the outer 100 ends of which are secured in a plate 23, carrying a set-screw 24, adapted to be turned into engagement with the pole member, and thereby clamp the offset 8 in its stop, the step-

engaging member 10 being held in its stop by reason of its inherent resiliency. To effect adjustment of the step, the set-screw 24 is loosened and the clamping member 10 thrown 5 out of engagement with its stop, after which the step is moved to the desired point and clamped in the position, as before.

In the form of embodiment of the invention shown in Fig. 3 the upper portion of the 10 slot-engaging member 25 is practically the same as that shown in Figs. 1 and 2; but the arms 26 are bent upon themselves and looped or hooked into the loop-engaging member at 27 to impart the necessary resiliency thereto 15 to cause it positively to engage its stop, those portions of the stop-engaging member lying against the step as well as the arms being secured in position by suitable fastening means, such as staples 28. The clamping member 29 is practically a yoke having its terminals bent at right angles to its 20 length and seated in openings 30 in the step. The crest of the yoke 29 has associated with it an eccentric-bearing lever 31, the head 32 25 of which is designed to bear against the rear side of the stilt, and thereby securely clamp the offset 8 in its stop. To effect adjustment of the step in this latter form of the embodiment of the invention, the lever is rocked to 30 move its head or eccentric out of engagement with the pole, and the step is then moved to the desired point, after which the eccentric is turned back to its locked position.

In the form of embodiment of the invention 35 shown in Fig. 4 the step is constructed of a single piece of resilient material having a rectangular opening to receive the pole and to present a lip or tongue 33 to engage a stop at the rear side of the pole and with an in- 40 turned lip or tongue 34 to engage a stop on the front side of the pole, and, if preferred, a screw or other form of fastening device 35 may be employed for holding the latter lip in engagement with the stop, although in practice the use of this supplemental device is 45 not absolutely essential, as the construction of the step is such as to cause the lips 33 and 34 positively to interlock with the stops.

In the form of embodiment of the invention 50 shown in Fig. 5 the step is constructed of a piece of wire having one terminal bent to present a rectangular pole-engaging member 36, thence twisted upon itself, as at 37, to present the step proper, the twisted portion 55 terminating at 38 in an upturned portion constituting a guard, and the ends of the wire are then diverged and passed around the side of the step 37 back to the pole, at which point they are again twisted together in a vertical 60 plane, as at 39, and the terminals are finally bent into two step-engaging members 40, which embrace the front and two sides of the pole, the ends of the terminals having associated with them a resilient clamping member 41, 65 which embraces the pole at two points. In this form of embodiment of the invention the stops 42 are disposed on the front side of the

pole and are engaged by the members 40, as above described, and to effect adjustment upon the pole the step is rocked upward to 70 throw the members 40 out of engagement with the stop, whereupon the step may be moved to another stop, and when released the clamping member 41 will instantly draw the members 40 into engagement with the stop. 75

In the form of embodiment of the invention shown in Fig. 6 the step is also constructed of a piece of wire bent to form a stop-engaging member 43, thence twisted upon itself to form a step proper, 44, thence into the end 80 coils 45, which constitute guards, thence backward and slightly below and parallel with the step 44, the ends being passed through the stop-engaging member 43, thence twisted upon themselves at 45, and thence bent around 85 the pole to present a clamping member 46, the stops 47 in this form of embodiment of the invention being at the rear of the pole.

In the forms of embodiment of the invention shown in Figs. 7 and 8 the step is constructed of two pieces of wire, one of which is bent to present a pole-engaging member 48 and thence twisted or plaited to present the step 49, the members then being turned and run rearward along the side of the step, 95 as at 50, thence turned over the pole-engaging member 48 and downward and twisted together, as at 51, the terminals being bent laterally and around to present pole-engaging members 52, the terminals of which are 100 flattened at 53 and have associated with them a resilient clamping member 54. The stops in the form of embodiment of the invention are composed of openings 55, which are adapted to be engaged by a stop-engaging 105 member 56, composed of a length of wire having one end bent to present the step-engaging member 56 and having the remainder of its length interwoven with the step 49, as shown at 57, and finally bent around 110 the clamping member adjacent to the pole, as shown at 58. To effect adjustment of the step, the same is moved upward to bring the member 56 out of engagement with the stop, whereupon the step may be moved to the desired point, and the member 56 will again 115 engage the stop and be held there by the clamping member 54.

Under each of the forms of embodiment shown and described simple and effective 120 provision is made for holding the step in its adjusted position on the pole and to permit of ready shifting when desired.

Having thus fully described my invention, what I claim as new, and desire to secure by 125 Letters Patent, is—

1. A stilt comprising a pole provided with stops, a step, and resilient pole-embracing means connected with the step and engaging the said stops. 130

2. A stilt comprising a pole provided with oppositely-disposed stops arranged in staggered order, a step provided with means for engaging the stops on one side of the pole,

and resilient means embracing the pole and engaging the stops on the other side thereof.

3. A stilt comprising a pole provided with oppositely-disposed stops arranged in staggered order, a step provided with means for engaging the stops on one side of the pole, resilient means embracing the pole and engaging the stops on the other side thereof, and pole-clamping means connected with the step.

10 4. A stilt comprising a pole, a step of re-

silient material, and means for fastening said step to said pole.

In testimony that I claim the foregoing as my own I have hereto affixed my signature in the presence of two witnesses.
